UNITED STATES PATENT OFFICE.

IRA G. NICKS, OF NORFOLK, VIRGINIA.

INTERNAL-COMBUSTION ENGINE.

1,214,357.

Specification of Letters Patent. Patented Jan. 30, 1917.

Application filed January 22, 1916. Serial No. 73,675.

To all whom it may concern:

Be it known that I, IRA G. NICKS, a citizen of the United States, residing at Norfolk, in the county of Norfolk and State of Virginia, have invented certain new and useful Improvements in Internal-Combustion Engines; and I do hereby declare the following to be a full, clear, and exact description of the invention, such as will enable others skilled in the art to which it appertains to make and use the same.

This invention relates to internal combustion engines, and more particularly to engines of the multiple piston four-cycle type.

The invention has for its primary object to provide an improved internal combustion engine including a hollow double piston in one end of which is rotatably mounted a fuel and exhaust controlling valve reciprocable with the piston and connected with the crank shaft of the engine.

Another object is the provision of an internal combustion engine including a cylinder having two combustion chambers in which is reciprocably mounted a double piston, the relatively large end of which is connected at diametrically opposed points with the crank shaft of the engine.

Another object is the provision of a novel type of driving connection between the crank shaft and rotary valve so constructed as to permit longitudinal movement of the valve with the piston.

Another object is the provision of an internal combustion engine embodying a circular plate supported internally of the relatively large end of the hollow piston to provide a compression chamber communicating with the intake ports of the rotary valve and in which the gaseous fuel for the engine is compressed.

With these and other objects in view, the invention consists in the novel construction, arrangement and formation of parts as will be hereinafter specifically described, claimed and illustrated in the accompanying drawing, in which:

Figure 1 represents a fragmental longitudinal sectional view through the improved engine, partly broken away. Fig. 2 represents a transverse sectional view on the line 2-2 of Fig. 1. Fig. 3 represents a transverse sectional view on the line 3-3 of Fig. 1. Fig. 4 represents a longitudinal sectional view through the valve and portions of the

piston and cylinder, in the plane of Fig. 1, illustrating the valve turned a half revolution with relation to its position as illustrated in Fig. 1.

Referring to the drawing in detail, where-in similar reference numerals designate corresponding parts throughout the several views, the numeral 5 indicates generally the cylinder of the engine, which includes the relatively small and large upper and lower portions 6 and 7, respectively. The cylinder 5 intermediate the relatively large and small portions thereof is bulged, as indicated at 8, to provide an internal explosion chamber 9, and the head 10 of the cylinder is also enlarged to define a combustion chamber 11. A double piston is slidably mounted within the cylinder and includes relatively small and large upper and lower portions 12 and 13, respectively, which are connected by the annular portion 14 defining a shoulder upon which is delivered the force of the explosions in the lower or relatively large combustion chamber 9. The double piston is of hollow formation and is provided adjacent its lower or relatively large free end with a pair of diametrically opposed laterally projecting pins 16.

The crank shaft 17 is rotatably supported in suitable bearings (not shown) below the cylinder 5 and is provided with the usual crank pins 18, which are connected with the diametrically opposed pins 16 of the piston by the connecting rods 19.

A supporting plate 20 is suitably supported above the crank shaft 17 intermediate the connecting rods 19 and is provided with a pair of depending bearings 21 supporting the crank shaft 17 intermediate the crank pins 18. A plurality of uprights 22 are secured in vertical position upon the plate 20 and are rigidly secured at their upper extremities to a circular plate 23 snugly and slidably received within the relatively large end 13 of the double piston. The plate 23 is formed with an aperture 24 connected with a fuel supply pipe 25 and in which is arranged an outwardly closing valve 26, normally retained in closed position by a spring 27 and designed to check the egress of gaseous fuel from the compression chamber 28 between the annular shoulder 14 and the circular plate 23.

A cylindrical valve, designated generally by the numeral 29, is snugly and rotatably

fitted in the relatively small end 12 of the piston and is secured against longitudinal movement therein by screw 30 or other suitable means. The upper extremity of a vertically disposed shaft 31 is non-rotatably secured centrally within the lower extremity of the rotary valve 29 and the lower portion of said shaft is squared and slidably and non-rotatably fitted in a correspondingly shaped sleeve 32. The sleeve 32 terminates in spaced relation above the crank shaft 17 and is secured at its lower extremity to a beveled gear wheel 33, which meshes with a beveled gear wheel 34 keyed upon the crank shaft 17, whereby rotary motion is imparted from said crank shaft through the beveled gear wheels 34 and 33, sleeve 32 and shaft 31 to the rotary valve 29, during reciprocation of the piston within the cylinder.

The valve 29 is formed with an angular fuel passage 36 communicating at its lower extremity with the compression chamber 28 and terminating in spaced relation to the upper extremity of the valve. During rotation of the valve 29 the upper extremity of the port or passage 36 is moved into registration with an aperture 37 formed adjacent the upper closed end of the relatively small portion 12 of the piston. The aperture 37 reciprocates over a groove 38 formed in the inner surface of the relatively small end 6 of the cylinder and is adapted, when the upper extremity of the passage or port 36 is moved into registration with the opening 37 to admit fuel to the combustion chamber 11 as the piston moves upwardly in the cylinder. As the piston moves over the upper extremity of the groove 38 the aperture 37 is closed by contact with the cylinder wall and thus the combustion chamber 11 is sealed so as to prevent leakage of the explosive. An exhaust port 40 for both combustion chambers 9 and 11 is formed in the reduced or relatively small portion 6 of the cylinder wall adjacent the annular shoulder 8 and is adapted to register with the port 40^a formed in the relatively small portion 12 of the piston during reciprocation of the latter. The upper portion of the rotary valve 29 is formed with an angular exhaust port 41 for the upper combustion chamber 11, and, during rotation of the valve is adapted to simultaneously register with the longitudinal groove 38 and the ports 40 and 40^a so as to permit the products of combustion to exhaust from the upper chamber 11.

A second and relatively short intake passage 44 is formed in the valve 29 below the exhaust passage or port 41 for the upper chamber 11 and the upper extremity thereof is adapted to register with the port 45 formed adjacent the longitudinal center of the reduced or relatively small portion 12 of the piston, during rotation of the valve so as

to conduct gaseous fuel from the compression chamber 28 to the explosion chamber 9 of the lower or relatively large portion 7 of the cylinder. An exhaust port 46 for the lower combustion chamber 9 is formed in the valve 29 in diametrically opposed relation to the intake port or passage 44 and is adapted, during rotation of the valve, to communicate the port 45 with the ports 40 and 40^a so as to permit of the escape of the products of combustion from the chamber 9 subsequent to an explosion therein.

The difference in size of the bevel gear wheels 33 and 34 is such that the valve 29 is given one complete revolution to two revolutions of the crank shaft 17.

The relatively small portion 6 of the cylinder is formed with apertures receiving oil pipes 50 and adapted to register with apertures 51 formed in the relatively small end 12 of the piston to permit distribution of a suitable lubricant over the bearing surfaces of the cylinder, piston and rotary valve. The valve 29 is formed with a circumferential groove 52 registering with the apertures 51 for containing oil.

In use, the fuel supply pipe 25 is connected with a suitable source of gaseous fuel which is drawn into the compression chamber 28 during the up stroke of the piston, and is subsequently compressed during the subsequent down stroke of said piston. Assuming that the valve 29 is in the position illustrated in Fig. 1, and rotates in the direction of the arrow illustrated in Fig. 2, the products of combustion are exhausted during the up-stroke of the piston, from the combustion chamber 9 through the ports 45, 46, 40^a and 40, while the compressed fuel in the chamber 28 is admitted to the upper portion of the upper extremity 6 of the cylinder through the ports 36, aperture 37 and groove 38. As the piston moves upwardly the gaseous fuel admitted to the upper combustion chamber 11 is compressed and subsequently ignited by a suitable ignition device (not shown). The force of the explosion in the chamber 11 drives the piston downwardly, imparting rotational movement to the crank shaft 17 through the pins 16 and connecting rods 19 and rotating the valve 29 through the beveled gear wheels 34-33, sleeve 32 and shaft 31. During the subsequent upstroke of the piston the valve 29 is moved into position to register the angular exhaust port 41 with the aperture 37 and groove 38 and the apertures 40 and 40^a, thus permitting the products of combustion from the inner extremity of the reduced end 6 of the cylinder to escape, and simultaneously registering the outer extremity of the intake port 44 with the port 45 in the reduced extremity 12 of the piston, thus permitting the compressed fuel in the chamber 28 to enter the chamber 9.

What I claim is:

1. In an internal combustion engine, a cylinder, a piston reciprocably mounted in said cylinder, a valve rotatably mounted in said piston, a crank shaft, connections between said piston and said crank shaft, driving connections between said valve and said crank shaft and relatively stationary supporting means for said driving connections.
2. In an internal combustion engine, a cylinder having a reduced end, a double piston including relatively large and small portions reciprocably mounted in said cylinder, a valve rotatably mounted in said piston, a crank shaft, extensible driving connections between said valve and said crank shaft and relatively stationary supporting means for said driving connections.
3. In an internal combustion engine, a cylinder having a reduced end and explosion chambers, a hollow double piston reciprocably mounted in said cylinder, a crank shaft, connections between the relatively large end of said piston and said crank shaft, a plate snugly fitted within the relatively large end of said piston providing a compression chamber, and a rotary valve mounted in said piston for connecting said explosion chambers with said compression chamber.
4. In an internal combustion engine, a cylinder having a reduced end, a double piston reciprocably mounted in said cylinder, a plate snugly fitted within the relatively large end of said piston, a valve rotatably mounted in the relatively small end of said piston, a crank shaft, driving connections between the relatively large end of said piston and said crank shaft, and driving connections between said crank shaft and said rotatable valve extending through said plate.
5. In an internal combustion engine, a cylinder, a piston reciprocably mounted in said cylinder, said cylinder having apertures therein, oil pipes communicating with said apertures, said piston having apertures adapted to be moved into registration with the apertures in said cylinder, and a valve rotatably mounted in said piston having a circumferential oil receiving groove registering with the apertures in said piston.
6. In an internal combustion engine, a cylinder having an internal explosion chamber, a hollow piston reciprocably mounted in said cylinder, a relatively stationary plate snugly fitting the open end of said piston providing a compression chamber, means for connecting said compression chamber with
- said explosion chamber, and a fuel pipe connected with said compression chamber.
7. In an internal combustion engine, a cylinder having one end reduced and internal explosion chambers, a double hollow piston reciprocably mounted in said cylinder having the relatively small end closed and the relatively large end open, a relatively stationary plate snugly fitted in the relatively large open end of said piston providing a compression chamber, and a cylindrical valve rotatably mounted in the relatively small end of said piston and provided with ports adapted to connect said compression chamber with said explosion chambers.
8. In an internal combustion engine, a cylinder having one end reduced and internal explosion chambers, a double hollow piston reciprocably mounted in said cylinder having spaced inlet and exhaust ports therein adapted for connection with said explosion chambers during reciprocation of the piston, the relatively small end of said cylinder having an exhaust port therein adapted to register with one of the ports of said piston, and a valve rotatably mounted in said piston having ports adapted to connect the explosion chambers with the exhaust ports in the piston and cylinder, when the latter are aligned, said rotary valve also having angular inlet ports adapted for connection with said internal explosion chamber.
9. In an internal combustion engine, a cylinder having one end reduced and provided with an exhaust port, a double hollow piston reciprocably mounted in said cylinder having the relatively small end closed and the relatively large end open, a relatively stationary plate fitted in the relatively large end of said piston providing a compression chamber, a fuel pipe connected with said compression chamber, said piston having inlet and exhaust ports therein, said cylinder having internal combustion chambers adapted for connection with the ports in said piston, and a rotary valve rotatably mounted in the relatively small end of said piston having angular inlet ports adapted to connect said compression chamber with said explosion chambers, and exhaust ports adapted to connect said explosion chambers with the exhaust ports in said cylinders.

In testimony whereof I affix my signature in presence of two witnesses.
